COMBINED DOOR-HOLDING AND DOOR-CHECKING DEVICE

Rudolph I. Schonitzer, Cleveland, Ohio

Application May 28, 1934, Serial No. 727,891

13 Claims. (Cl. 16—86)

This invention relates to a combined door-holding and door-checking device, the device being especially adapted for use with the hinged doors of automobiles and the like.

5 Many of the doors of present day automobiles are hingedly mounted on inclined body posts or pillars, with the result that said doors have a natural tendency to swing to closed position. The undesired closing movement of automobile doors as the result of such tendency has resulted in serious personal injury, and the provision of a means for releasably holding such doors in open position whenever they are moved thereto is quite desirable if not absolutely necessary.

10 15 The general object of the present invention, therefore, is the provision of a simple and improved device for releasably holding a hinged door in open position, such holding of said door being easily and conveniently effected by the ordinary manual operation of moving the door to such position and the release of said door being easily and conveniently effected by the ordinary manual operation of moving the door from such position.

20 25 A further object of the present invention is the provision of a simple and improved device which not only is capable of releasably holding a hinged door in open position whenever it is moved thereto but also, is capable of checking the opening movement thereof, thereby making unnecessary the use of a separate door check therefor.

30 35 A further object of the present invention is the provision of a simple and improved door-holding and door-checking device which is adapted for simple securement to intermediate portions of the hinge side of a door and the hinge side of a body post or pillar on which such door is hingedly mounted, the parts of said device being almost entirely enclosed within and hence concealed by said door and said post or pillar, even when the door is in open position.

40 45 Further objects of the present invention are to provide for structural simplicity, compactness, manufacturing economy, and certainty of operation under all predetermined conditions.

50 55 With the foregoing and other objects in view which will appear as the description of the present invention proceeds, said invention resides in the combination and arrangement of parts and in the details of construction hereinafter described and claimed, it being understood that changes in the present invention as herein disclosed can be made within the scope of what is claimed without departing from the spirit of the invention.

The invention will be readily understood from the following detailed description of one embodiment thereof, reference being had to the accompanying drawing in which

5 Fig. 1 is a side elevation of a portion of an automobile body constructed in accordance with present day stream-line designs, each of the generally hollow four doors of said body (two of which are shown) having associated therewith a combined door-holding and door-checking device embodying the present invention; Fig. 2 is a horizontal, longitudinal sectional view of a portion of the hinge side of the left front door of said body and a portion of the hinge side of the inclined and generally hollow post or pillar thereof on which said door is hingedly mounted, the door being in closed position and the holding and checking device therefor being in inoperative position, the view being on the line 2—2, Fig. 1; Fig. 3 is a view similar to Fig. 2 but showing the door releasably held in open position by said device; Fig. 4 is a detail vertical, longitudinal sectional view of the holding and checking parts of said device, the view being on the line 4—4, Fig. 3; Fig. 5 is a detail vertical, cross sectional view of parts of said device, the view being on the line 5—5, Fig. 4; Fig. 6 is a detail vertical, longitudinal sectional view of parts of said device, the view being on the line 6—6, Fig. 5; and Fig. 7 is a detail vertical, cross sectional view of the checking member of the present device and the arm or link thereof on which it is mounted, the view being on the line 7—7, Fig. 3.

20 25 30 35 40 45 50 55 In the portion of the automobile body shown in Fig. 1, 1 represents the generally hollow left front door and 2 the generally hollow left rear door, the front door having its front or hinge side mounted by the usual hinges 3 on the hinge side of the rearwardly inclined and generally hollow front post or pillar 4 of said body and the rear door having its rear or hinge side mounted by the usual hinges 5 on the hinge side of the slightly forwardly inclined and generally hollow rear post or pillar 6 of such body. Because of the inclination of said body posts or pillars, the tendency of both doors is to swing to closed position, the front door swinging rearwardly to such position and the rear door swinging forwardly to such position. Inasmuch as the doors of the larger automobiles are relatively heavy, serious personal injury easily may result, and in fact has resulted, from undesired closing movement of said doors as the result of such tendency.

To effectively prevent undesired closing movement of hinged doors, such as automobile doors,

the device of the present application was provided, the chief function of which device is to releasably and automatically hold a hinged door in open position whenever it is moved thereto.

5 To avoid the necessity of using a separate device for checking the opening movement of such a door, the present device is so constructed that it also functions as a door check or door cushioning means, all as will hereinafter more fully appear.

10 For purposes of illustration, the details of construction of the holding and checking device for the left front door of the automobile body of Fig. 1 are shown in Figs. 2 to 7 inclusive of the accompanying drawing, it being understood that 15 the holding and checking devices for the other doors of said body are of like construction.

As shown, the present improved door-holding and door-checking device includes a relatively flat and longitudinally bent metal arm or link 10 having its rear end pivotally or otherwise suitably connected to an intermediate portion of the hinged side of the door 1, such as between the two hinges 3 thereof. The connection of said arm or link to said door is preferably of the concealed type, the rear end of said arm or link being pivotally connected to a bifurcated lug 12 arranged within said generally hollow door and welded or otherwise suitably secured to the front edge wall 13 thereof, said wall being provided with a suitable slot 14 through which said arm or link extends.

The front or free end portion of said arm or link lies within the generally hollow body post or pillar 4, the rear edge wall 18 of which is provided with a suitable slot 19 through which said arm or link extends. As clearly shown in Figs. 2 and 3, the generally horizontal dimension of the slot or opening 19 of the edge wall 18 of the body post or pillar 4 is substantially less than the corresponding dimension of such edge wall, so that said body post or pillar, which is of generally hollow form, is not appreciably weakened by the provision of such slot or opening. The use of a slot or opening having its generally horizontal dimension so restricted or limited is possible because of the longitudinal bending of the arm or link 10, as will be readily understood from an examination of the accompanying drawing. Located within said post or pillar and welded or otherwise rigidly secured on the free end of said arm or link is a suitable retainable means of projecting character, here shown as a pair of oppositely extending wings 20 which constitute the end portions of a rigid metal bar having its middle portion 21 bent into substantially U-form to receive and be rigidly secured to the free end of said arm or link.

Longitudinally arranged within the generally hollow body post or pillar 4 and welded or otherwise suitably secured to the rear edge wall 18 thereof, over the arm or link-receiving slot 19 therein, is a suitable retaining means for releasable holding engagement with the wings 20 of the arm or link 10, the retaining means here shown being of unit form and comprising a generally rectangular metallic base plate 25, a pair of metallic retaining leaf springs 26 and a generally rectangular metallic cover plate 27, the latter overlying said base plate and having its longitudinal side edge portions welded at 28 or otherwise suitably secured thereto. A longitudinally disposed offset portion 30 of said cover plate provides therebeneath a correspondingly disposed cavity 31 in opposite end portions of which are rigidly secured laterally bent base portions 32 of

the two retaining springs 26, such securing being simply and economically maintained by laterally extending spring-engaging end flanges 33 with which the base plate 25 is integrally provided. The two retaining springs 26 are thus 5 securely maintained in spaced relation, one above the other, on opposite sides of the plane of the path of pivotal movement of the arm or link 10, as shown.

As before mentioned, the aforesaid retaining 10 unit is longitudinally positioned over the arm or link-receiving slot 19 of the body post or pillar edge wall 18, and to permit said arm or link to extend through said retaining unit to effect releasable holding engagement of its wings 20 with 15 the springs 26 of said retaining unit, the base plate 25 and the cover plate 27 of said unit are each provided with a suitable slot to receive said arm or link, the two slots of said base and cover plates and the slot 19 of said post or pillar edge 20 wall 18 being in alignment or registration, as shown.

As best shown in Fig. 4, the two retaining springs 26 have a pair of outwardly flaring free end portions 40, a pair of restricted neck portions 25 41 adjacent thereto and a pair of relatively abrupt retaining shoulder portions 42 adjacent said neck portions. The retainable wings 20 of the arm or link 10 have a pair of end shoulder portions 44 corresponding to and adapted for cooperation 30 with the retaining shoulder portions 42 of the retaining springs 26 and said retainable wings also have a pair of side wall portions 45 corresponding to and adapted for cooperation with the free end portions 40 of said retaining springs. 35

When the door 1 is in closed position, as in Figs. 1 and 2, the major portion of the arm or link 10 of the present improved device lies within the generally hollow body post or pillar 4, the intermediate portion of said arm or link lying between 40 the two retaining springs 26, as shown. Upon opening movement of said door, the major portion of said arm or link is withdrawn from said body post or pillar, said arm or link moving clockwise (Figs. 2 and 3) with said door and the retainable wings 20 of said arm or link being yieldingly pulled between said retaining springs into releasable holding engagement therewith, as shown in Figs. 3 and 4. Due to the more or less gradual curvature of the free end portions 40 of said retaining springs and the side wall portions 45 of 50 said arm or link wings, little resistance is offered to the inward passage of said wings between and beyond said spring free end portions, but due to the abruptness of the shoulder portions 42 of said springs and the end shoulder portions 44 of said 55 wings, sufficient resistance to outward movement of said wings is afforded to effectively hold said door in fully open position, subject to its release, of course, whenever desired, as the resistance to the release of said wings is not sufficient to prevent the ordinary manual closing of the door. 60

In order to limit lateral or pivotal movement of the arm or link 10, and thus insure cooperative engagement, for door-holding purposes, of the 65 arm or link wings 20 and the retaining springs 26, any suitable means cooperable with said arm or link between its wings 20 and its pivot may be utilized. As here shown, a suitable rubber bushing 35 is secured in the slots of the base and cover 70 plates 25 and 27 of the retaining unit, and through such bushing the arm or link 10 extends. As a result, the pivotal movement of said arm or link is effectively limited by those portions of the bushing which are disposed in the plane of the path 75

of pivotal movement of said arm or link. Inasmuch as said bushing is of resilient character, the pivotal movement of said arm or link is not only limited but desirably cushioned, all as will be readily understood.

It will thus be seen that the present device is effective to firmly and automatically hold a door in fully open position whenever it is moved thereto but is ineffective to prevent the ordinary manual closing thereof when desired.

In order to enable the present improved device to also function as a door check, to check outward or opening movement of the door with which it is associated, the arm or link 10 of the device is here provided adjacent its retainable wings 20 with suitable resilient means for such door checking purposes. Although said checking means may be in the form of one or more springs or the like, it is here shown as a solid rubber member 50 provided with a suitable slot 51 through which said arm or link extends, said slot being of such size that said member is frictionally maintained adjacent the wings 20 of said arm or link, as shown.

Upon opening movement of the door 1, said checking member 50 moves inwardly with the free end portion of the arm or link 10 between the two retaining springs 26 and is yieldingly compressed between the wings 20 of said arm or link and the rubber bushing 35 of the base and cover plates 25 and 21. As a result, the final portion of the door opening movement is effectively checked, in the same manner as that accomplished by the ordinary door checks now used with automobile doors.

As best shown in Fig. 4, the depth of the checking member 50 is such that it does not interfere with the inward movement of the arm or link wings 20 between and beyond the free end portions 40 of the retaining springs 26, the door 1 being held in open position with a slight looseness or play, as will be readily understood.

Inasmuch as the free end portion of the arm or link 10, upon which said checking member 50 is mounted has some lateral movement within the generally hollow body post or pillar 4 when the door is in closed position, said checking member is provided in the embodiment of the invention here shown with a projecting side fin 54, the purpose of which is to yieldingly engage the side wall 56 of said body post or pillar upon outward lateral or pivotal movement of said arm or link free end portion and thus absorb any noise which might otherwise result therefrom. The checking member 50 here shown is also provided, opposite the fin 54, with a second fin 55 for yieldable engagement with the side wall 57 of the body post or pillar 4 upon inward lateral or pivotal movement of the free end portion of the arm or link 10 when the door 1 is in closed position. Because of its reduced size, however, the fin 55 will engage the body post or pillar side wall 57 only if the bushing 35 for the arm or link 10 becomes excessively worn as the result of pivotal movement of said arm or link, as will be readily understood.

From the foregoing, it will be apparent that the present improved device effectively accomplishes the dual function of releasably holding a hinged door in open position whenever it is moved thereto and of checking the outward or opening movement thereof; that the parts of the device are of simple and durable form and are readily and conveniently connected to intermediate portions of the hinge sides of a door and a body post or pillar. The retaining means of the

device is secured to the body post or pillar as a unit, the securement thereof being effected by the use of screws, rivets or a welding operation. If desired and as here shown, the base plate 25 of said retaining means may be provided with laterally bent side flanges 60, the purpose of which is to give said plate increased strength and rigidity. To insure permanency of location of the base portions 32 of the two retaining springs 26 between the base and cover plates 25 and 21, the offset portion 38 of said cover plate, at the sides of the arm or link-receiving slot therein, may be provided with integral tongues 62 engaging in notches 63 in the inner ends of said spring base portions, all as clearly shown in Fig. 5.

It is to be noted that the present improved device may be operatively associated with a hinged door and the post, pillar or frame on which said door is mounted with the retaining means of the device arranged either in the door, as shown with the front door 1 of the automobile body of Fig. 1, or in the post, pillar or frame, as shown with the rear door 2 of said body, all as will be readily understood.

Although the drawing of the present application illustrates and the specification describes the use of the present improved device with automobile doors mounted on inclined axes, it is to be understood that said device is equally applicable for use with doors mounted on vertical or non-inclined axes, inasmuch as said doors also are subjected to undesired closing tendencies by winds, the parking of the automobiles of which they are a part on inclined surfaces, etc.

It is also to be understood that the invention here involved may be used for door-holding purposes only, either with or without separate door-checking means, all within the scope of the appended claims.

What I claim is:

1. In a device for releasably holding a hinged door in open position, a retaining unit comprising an attaching base plate, a pair of retaining spring portions having laterally extending spaced base parts, and a cover plate overlying the base parts of said spring portions and secured to said base plate, said base and cover plates being provided between the base parts of said spring portions with strap or link-receiving openings.

2. In a device for releasably holding a hinged door in open position, a retaining unit comprising an attaching base plate, a cover plate secured thereto and having portions thereof spaced therefrom to provide a pair of elongated cavities therebetween, a pair of retaining members each having a laterally extending base part lying in one of said cavities and endwise insertable thereto, and end flanges carried by said base plate and engaging said retaining members for preventing their endwise removal from such cavities.

3. In a device for releasably holding a hinged door in open position, a retaining unit comprising an attaching base plate, a cover plate secured thereto and having portions thereof spaced therefrom to provide a pair of elongated cavities therebetween, a pair of retaining members each having a laterally extending base part lying in one of said cavities, means for closing the inner ends of said cavities to prevent converging movement of said retaining members, and end flanges carried by said base plate and engaging said retaining members for preventing

diverging movement of said retaining members, whereby the base parts of said retaining members are securely maintained in such cavities.

4. A device for releasably holding in open position a door member having a side thereof hinged on a side of a supporting member and for checking the opening movement of said door member, said device comprising an arm adapted to be pivotally secured to the hinge side of one of said members, means adapted to be secured to and enclosed within the other of said members and having a retaining portion, a retainable portion carried by said arm within said last mentioned member for releasable retention by the retaining portion of said means when said door member reaches a predetermined open position, whereby said door member may be releasably held in such open position, and cooperating checking portions, one associated with said arm and the other associated with said means and adapted to abut each other as the door member approaches open position for checking its movement.
5. A device for releasably holding in open position a door member having a side thereof hinged on a side of a supporting member and for checking the opening movement of said door member, said device comprising an arm adapted to be pivotally secured to the hinged side of one of said members, retaining means adapted to be secured to and enclosed within the other of said members, a retainable head carried by said arm within said last mentioned member for releasable retention by said retaining means when said door member reaches a predetermined open position, whereby said door member may be releasably held in such open position, and a yieldable checking part on said arm between said head and a part of said retaining means and adapted to abut such part as the door member approaches open position for yieldably checking its movement.

6. In a device of the class described, in combination, a door check comprising a check arm, a resilient checking member mounted upon the free end portion of said check arm, retainable means fixed to the check arm to hold the checking member from displacement and having a portion projecting outwardly beyond said checking member, and a resilient stop adapted to be mounted for cooperation with the check arm and comprising spaced spring fingers between which the checking member is adapted to be received, said fingers being provided with recesses adapted to receive the projecting portion of the retainable means, whereby to resiliently engage the same for holding the check arm and the checking member in a predetermined position after relative movement of these parts.

7. A device for releasably holding in an open position a door member hinged on a supporting member, said device comprising a longitudinally bent arm adapted to be pivotally secured to one of said members and to extend into the other of said members, said arm being provided with retainable means within said last mentioned member, retaining means adapted to be secured to and enclosed by said last mentioned member for cooperative engagement with the retainable means of said arm in releasably holding said door member in an open position, and means cooperable with said arm between its pivot and the retainable means of such arm for so limiting the pivotal movement of said arm as to insure cooperative engagement of the retainable means of said arm and

said retaining means when said door member approaches such open position.

8. A device for releasably holding in an open position a door member hinged on a supporting member, said device comprising a longitudinally bent arm adapted to be pivotally secured to one of said members and to extend into the other of said members, said arm being provided with retainable means within said last mentioned member, and retaining means adapted to be secured to and enclosed by said last mentioned member for cooperative engagement with the retainable means of said arm in releasably holding said door member in an open position, said retaining means having retaining parts arranged in opposed relation on opposite sides of the plane of the path of pivotal movement of said arm.

9. A device for releasably holding in an open position a door member hinged on a supporting member, said device comprising a longitudinally bent arm adapted to be pivotally secured to one of said members and to extend into the other of said members, said arm being provided with retainable means within said last mentioned member, retaining means adapted to be secured to and enclosed by said last mentioned member for cooperative engagement with the retainable means of said arm in releasably holding the door member in an open position, said retaining means having retaining parts arranged in opposed relation on opposite sides of the plane of the path of pivotal movement of said arm, and means in the plane of the path of pivotal movement of said arm and cooperable with said arm between its pivot and the retainable means of such arm for so limiting the pivotal movement of said arm as to insure cooperative engagement of the retainable means of said arm and said retaining means when said door member approaches such open position.

10. A device for releasably holding in an open position a generally hollow automobile door member hinged on a generally hollow body pillar member or the like, said device comprising a longitudinally bent arm adapted to be pivotally secured to one of said members and to extend into the other of said members through an edge wall opening with which said last mentioned member is provided, the generally horizontal dimension of said opening being substantially less than the corresponding dimension of such edge wall so that the member which is provided with such opening is not appreciably weakened thereby, the longitudinal bending of said arm enabling it to extend through such opening, said arm being provided with retainable means within the member into which said arm extends, and retaining means adapted to be secured to and enclosed by said last mentioned member for cooperative engagement with the retainable means of said arm for releasably holding the door member in an open position, said retaining means having engagement with the retainable means of said arm only when said door member is in substantially such open position.

11. A device for checking the opening movement of a door member hinged on a supporting member and for releasably holding said door member in an open position, said device comprising a longitudinally bent arm adapted to be pivotally secured to one of said members and to extend into the other of said members, means carried by said arm within said last mentioned member and having a retainable portion, retaining means adapted to be secured to and enclosed by said last mentioned member for cooperative en-

gagement with the retainable portion of said arm carried means in releasably holding said door member in an open position, and said arm carried means also having a checking portion for checking contact with a portion associated with the member into which said arm extends for checking the opening movement of said door member.

12. A device for checking the opening movement of a door member hinged on a supporting member and for releasably holding said door member in an open position, said device comprising a longitudinally bent arm adapted to be pivotally secured to one of said members and to extend into the other of said members, means carried by said arm within said last mentioned member and having a retainable portion, retaining means adapted to be secured to and enclosed by said last mentioned member for cooperative engagement with the retainable portion of said arm carried means in releasably holding said door member in an open position, means cooperative with said arm between its pivot and the means carried by said arm for so limiting the pivotal movement of said arm as to insure cooperative engagement of the retainable portion of said arm carried means and said retaining means

when said door member approaches such open position, and said arm carried means also having a checking portion for checking contact with a portion associated with the member into which said arm extends for checking the opening movement of said door member. 5

13. A device for checking the opening movement of a door member hinged on a supporting member and for releasably holding said door member in an open position, said device comprising a longitudinally bent arm adapted to be pivotally secured to one of said members and to extend into the other of said members, said arm being provided within said last mentioned member with retainable means and with a separate 15 checking member, retaining means adapted to be secured to and enclosed by said last mentioned member for cooperative engagement with the retainable means of said arm in releasably holding said door member in an open position, and the 20 checking member of said arm having checking contact when the door member reaches a predetermined open position with a portion associated with the member into which said arm extends for checking further opening movement of said 25 door member.

RUDOLPH I. SCHONITZER.
